SNOW SHOVEL

Everett H. Bickley, Bala-Cynwyd, Pa.

Application March 19, 1948, Serial No. 15,829

5 Claims. (Cl. 294—58)

1

The present invention relates to shovels and more particularly to an improved snow removing shovel.

In the use of snow shovels now on the market the user has to grasp a hand grip with one hand and then grasp the handle with the other hand at some place between the hand grip and the scoop. Thus, to scoop up a load of snow the user must bend well over to carry out the operations of lifting and then throwing the snow to one side. This is not only excessively tiring, but involves the necessary effort to raise the user's body to an erect discharging position. While it has heretofore been proposed to equip shovels with an auxiliary handle to lessen the effort in shovelling, these have not met the requirements for snow removal, in that some are too short to permit erect shovelling, while all fail to so attach the auxiliary handle as to allow the free universal action necessary to throw the material sideways during discharge, and at the most effective place on the scoop.

Some of the objects of the present invention are: to provide an improved shovel of the type having an auxiliary handle; to provide an improved snow shovel capable of loading, lifting and discharging while the user is in an upright position; to provide an improved snow shovel that lifts the load from a point substantially within the scoop area to take the leverage off the arms of the user; to provide a shovel that can be tilted in any position freely for throwing snow sideways; to provide a snow shovel that is extremely light in weight, comfortable to use, and cheap to construct; and to provide other improvements as will hereinafter appear.

In the accompanying drawings, Fig. 1 represents a perspective of a snow shovel embodying one form of the present invention; Fig. 2 represents a side elevation of the same; Fig. 3 represents a fragmentary section medially of the scoop and on a larger scale; Fig. 4 represents the shovel in the hands of the user showing erect scooping position; and Fig. 5 represents the shovel in the hands of the user showing erect discharge position.

Referring to the drawings, one form of the present invention is shown as applied to a shovel of the snow shovel type, wherein a scoop 10, preferably of arcuate configuration is carried by a handle 11 which terminates in a hand grip 12. The length of the handle 11 is such that when the scoop 10 rests on the ground the hand grip 12 is conveniently positioned to be grasped by the user while the latter is in an erect position.

2

In order to lift the scoop 10, while loaded, and at the same time allow the user to maintain an erect position while lifting and throwing the contents of the scoop to one side, an auxiliary hand grip 13 is provided and forms the free end of a wire or other loop 14, which traverses the eye 15 of a pivot pin 16. In the present instance, the pin 16 is a suitable cotter pin which passes through the scoop 10 from the front thereof to extend through the end portion of the handle 11 located on the back of the scoop 10. When properly located, the split ends of the pin 16 are bent in the usual manner to retain the parts in assembled condition. The location of the pin 16 on the scoop 10 is important and is preferably at a point on the longitudinal axis of the scoop but so spaced from the back edge of the scoop as to provide an effective leverage for the arms of the user while always in an erect position.

20 When the shovel is not in use the auxiliary hand grip 13 can be removably secured to the shovel handle 11 in any suitable or practical manner, the preferred means comprising a round-headed screw 17 which is screwed into the wooden hand grip 13 to project from the side which is juxtaposed to the shovel handle 11. Preferably, the handle 11 is of tubular aluminum and has a hole 18 located in the face thereof at such a location as will allow the head of the screw 17 to enter and thus anchor the auxiliary handle unit closely against the shovel handle 11.

30 In operation the user, while standing erect, can grasp both hand grips while the work edge of the scoop 10 rests upon the ground, and then using the arm which controls the hand grip 12, the handle 11 carrying the scoop 10 can be pushed forward without altering the user's erect position. No bending whatever is necessary. The scoop 10 now being loaded with snow or other material, the other arm of the user, through the medium 35 of the auxiliary hand grip 13, lifts the scoop 10 and throws the material off of the scoop and to one side. The substantially universal joint formed by the novel cotter pin construction aids materially in the proper sideways discharge of the material. While the present invention is primarily for use in snow removal, it can be applied to other types of shovels, i. e. for digging the auxiliary handle is made an amount longer, equal to the amount the implement is desired to enter the material dug.

Having thus described my invention, I claim:

1. As a new article of manufacture, a shovel comprising a scoop, a handle attached to said scoop and terminating in a hand grip, an auxil-

iary handle having a length to be grasped by the user in an erect position, and means to attach said auxiliary handle to said scoop at a point in close proximity to the center of said scoop.

2. As a new article of manufacture, a shovel comprising a scoop, a handle attached to said scoop and terminating in a hand grip, an auxiliary handle having a length to be grasped by the user in an erect position, and means to attach said auxiliary handle to said scoop at a point in close proximity to the center of said scoop, said means including a universal joint.

3. As a new article of manufacture, a shovel comprising a scoop, a handle attached to said scoop and terminating in a hand grip, an auxiliary handle having a length to be grasped by the user in an erect position, a pivot located medially of said scoop between the center and the back edge thereof, and means to attach said auxiliary handle to said pivot.

4. As a new article of manufacture, a shovel comprising a scoop, a handle attached to said scoop and terminating in a hand grip to be grasped by a user in an erect position, an auxiliary hand grip, a cotter pin traversing said scoop

10
15

at an effective leverage point, and a wire loop through said cotter pin with its ends attached to said auxiliary hand grip, said loop having a length to permit its hand grip to be grasped while the user is in an erect position.

5. As a new article of manufacture, a shovel comprising a scoop, a handle therefore, and extended lifting means universally attached within the area of said scoop.
